FRANK H. PAGE, OF SPRINGFIELD, MASSACHUSETTS.

CHOCOLATE-REFINING APPARATUS.

1,176,722.

Specification of Letters Patent. Patented Mar. 21, 1916.

Application filed January 29, 1915. Serial No. 5,024.

To all whom it may concern:

Be it known that I, FRANK H. PAGE, a citizen of the United States of America, residing in the city of Springfield, county of 5 Hampden, and State of Massachusetts, have invented certain new and useful Improvements in Chocolate-Refining Apparatus, of which the following is a specification.

This invention relates to chocolate refining apparatus. In particular it pertains to 10 that class of apparatus wherein the chocolate is refined by a rubbing action. Such a rubbing action is commonly accomplished by a granite roll reciprocable upon a granite 15 bed in a tank containing the chocolate to be refined.

In refining apparatus of this class, it has been found by experience that there is a 20 definite limit in the size to which the tank may be built. Beyond this limit, an increase in size reduces the efficiency of the refining action. Therefore, it is not practical to provide for increased capacity by employing 25 tanks of extra large size. Hence, instead of one large tank, it is preferable to use a number of smaller tanks in order to retain the highest efficiency in refining the chocolate. In large factories, where such refining machines are used in great numbers, this limitation of size now necessitates the occupation 30 of a large area of valuable floor space to accommodate the many small tanks.

It is an object of this invention to provide 35 an improved refining apparatus which embodies a number of individual refining tanks grouped and connected together into a single improved machine, having a main frame, whereby a maximum aggregate capacity is obtained with a minimum occupation of 40 floor space.

Another object of the invention is to arrange the plurality of operating devices in a new and useful manner, so that the assembled devices will operate as an improved 45 unit.

A further object is to provide an apparatus of the class described, wherein maximum capacity with a minimum occupation of floor space is combined with the greatest efficiency of operation.

In the accompanying drawings, wherein I

illustrate one preferred form of my invention: Figure 1 is a front elevational view of my improved refining apparatus; Fig. 2 is a plan view thereof; Fig. 3 is an end elevational view; Fig. 4 is a sectional elevation of a portion of one of the upper tanks of my apparatus showing the outlet and gate therefor; Fig. 5 is a view similar to Fig. 4, showing the outlet opened.

Referring to the drawings in detail; Figs. 1, 2, and 3 indicate four units A, B, C, and D of my refining apparatus supported upon a floor and mounted on the units are four other similar units E, F, G, and H, respectively. All of these tanks are similarly constructed and a description of one thereof will suffice for all. The tank B comprises a tank-like structure open at the top and suitably supported by legs as shown. The bottom of the tank is slightly curved and is provided with a bed 1 of stone. In contact with the latter is a roll b', of the same material, which is reciprocable on the bed by an operating rod b in a manner to be described. 70 Each of the other tanks has a similar roll and operating rod as a, c, d, e, f, g, and h, respectively.

Mounted between and supported on each lower pair of tanks A, B, and C, D, are 80 frames I, which rotatably support a main driving shaft 2 and a shaft 3. The frames I bear other frames J, and in the latter another shaft 4 is journaled. The shaft 2 may be suitably driven from any source by 85 the pulley shown and the shafts 3 and 4 are driven therefrom at equal speeds, by the gearing shown. Fixed on opposite ends of the shaft 3 and in opposed relation are cranks 6 and 7 and similarly arranged on 90 the shaft 4 cranks 8 and 9. Each of the cranks has pivotally connected thereto a pair of operating rods, for example the crank 6 has connected thereto the rods a and b and the crank 7, the rods c and d. The 95 upper operating rods e, f, and g h are similarly connected to the cranks 8 and 9, respectively. The rolls in the tanks are reciprocable by these cranks and operating rods in an obvious manner. It is to be noted 100 that the opposed cranks 8 and 9 are set in perpendicular relation to the opposed cranks

6 and 7 respectively. Thus the four cranks are virtually arranged at ninety degrees to one another, which arrangement yields a nicely balanced driving mechanism wherein 5 the strains due to reversing the direction of movement of the heavy rolls are balanced and transferred between shafts 3 and 4 and their connected rolls.

Each of the tanks is adapted to receive 10 chocolate, which is introduced from the top of the tank. The top openings in the four upper tanks are provided with removable covers 10, the one for the tank H being shown removed in Fig. 2. The top openings in the four lower tanks are closed by the covers 11 applied between the legs of the upper tanks, which are readily removable by the handles shown. After the chocolate has been sufficiently refined it may be 20 removed from the four lower tanks by dipping. Such a process, however, is not convenient for the four upper tanks and special outlets are accordingly provided. One of the latter is clearly shown in Figs. 4 and 25 5, which show the outlet in closed and open condition, respectively. An outlet 12 leads to a sloping trough 19 and, when the former is open, the chocolate readily passes from the tank by gravity. The side walls of the 30 trough 19 have ways 18, in which a cover 13 provided with a handle 17 is slidable. Formed on the side walls of the trough 19 and below the ways 18 are lugs 16, shaped as shown in Fig. 5. These lugs are adapted 35 to support a cross bar 14 in which is mounted a threaded rod 15. One end of the latter, when turned engages the plate 13 and forces the same against the lower walls of the outlet 12. On account of the removable mounting 40 of the plate 13 and bar 16 an unobstructed passage for the chocolate which can be readily cleaned is obtained, when the outlet is open.

One of the principal advantages of the 45 apparatus in addition to the balanced driving arrangement described lies in its economy of floor space. Thus, by the superposition of the upper tanks upon the lower the capacity of the apparatus may 50 be doubled without the use of additional floor space. If the capacity of the plant is not increased a saving of half the floor space formerly used is obviously made, but in fact an even greater saving in floor space 55 is effected by this arrangement as will be explained. It is necessary that each tank be conveniently filled, emptied and inspected. As a consequence, aisles are desirable between and at the sides of the tanks. If 60 we consider eight tanks arranged on the floor in pairs as shown five aisles would be necessary, two at the extreme sides and one (as at K, Fig. 2) between each pair. However, when four tanks are superposed upon

four other tanks, three aisles only are required. Thus, a saving of the space occupied by four tanks plus two aisles is obtained by my arrangement.

Heretofore, on account of the limitation of size of the refining tanks a large amount 70 of space has been necessary since each individual tank was placed directly upon the floor. In large factories the extended area necessary for these machines has been a hardship imposed on the users of refining 75 apparatus. My improved machine permits greatly increased capacity without added floor space or decreased floor space with the same capacity and is thus economically arranged.

In the former arrangement, embodying a plurality of tanks each supported on the floor, the tanks were arranged in opposed pairs and an operating shaft extended between each pair to drive all of the operating 85 rods. If eight tanks were so distributed a shaft more than double the length required in my apparatus would be necessary. Consequently, due to four cranks arranged at intervals on a long shaft, severe torsional 90 strains would be placed on the shaft. Furthermore, this arrangement does not permit balancing of the cranks and considerable vibration in the operation of the machine 95 would result.

My preferred apparatus embodies two very short shafts geared together to run at equal speeds. Each of these shafts has thereon cranks arranged in opposed relation and the cranks on one shaft are arranged 100 rectangularly to those on the other shaft. Thus, the load on the machine is equally distributed on account of these balanced operating cranks. Vibration is accordingly reduced to a minimum value as are the frictional losses of transmission. The saving in floor space particularly the additional saving due to a minimum number of aisles without losing the advantage of tanks of 105 efficient size is of particular importance.

Thus I have provided by my invention a compactly arranged refining apparatus which is operable at the highest efficiency and yet provides a maximum capacity for a minimum amount of floor space. It is recognized that many modifications may be made in the structure described without departing from the scope of my invention 115 which is defined in the appended claim.

What I claim is:

A chocolate refining apparatus comprising as a unit, a main frame, separate containing tanks, two pairs arranged at one level and another two pairs superimposed thereon, a reciprocable rubbing roll in each 125 tank, a main driving shaft, two crank shafts, one located above the other and each driven from the main shaft, a crank for each pair

of rubbing rolls, operable connecting means between the cranks and rolls, the rolls of the tanks at one level being connected with the cranks on one shaft and those at the other level being connected with the cranks on the other shaft, the two cranks on each shaft being arranged at 180 degrees with

respect to each other and at 90 degrees with respect to the cranks on the other shaft.

FRANK H. PAGE.
